United States Patent Office

Des. 195,567
Patented July 2, 1963

195,567

VALET STAND

Harold Gleitsman, New Rochelle, and Carl Fuerst, Bronx, N.Y., and John H. Squadra, Westport, Conn., assignors to Gleitsman's, Inc., Long Island City, N.Y., a corporation of New York

Filed Nov. 30, 1962, Ser. No. 72,662

Term of patent 14 years

(Cl. D33—8)

FIG. 1

FIG. 2

FIG. 3

FIG. 4

FIG. 5

FIG. 1 is a front perspective view of the valet stand, showing our new design;

FIG. 2 is a rear elevation view thereof;

FIG. 3 is a side elevation view thereof;

FIG. 4 is a top view thereof; and

FIG. 5 is a bottom view thereof.

We claim:

The ornamental design for a valet stand, substantially as shown.
